ORVILLE J. THOMPSON, OF FRANKLIN, PENNSYLVANIA

FISHING TOOL FOR SUCKER RODS

Application filed July 17, 1929. Serial No. 378,915.

This invention has for its object the production of a simple, efficient and comparatively inexpensive tool whereby sucker rods may be recovered from the tubing of a well 5 when the rod has become broken at a point intermediate the joints and thus becomes severed from its upper portion so that it cannot thereby be withdrawn from the tubing.

The construction of my improved fishing 10 tool for sucker rods is clearly shown in the accompanying drawings in which:

Fig. 1 is a side elevation of the top member of the tool.

Fig. 2 is a side elevation of the chuck 15 body.

Fig. 3 is a side elevation of the bottom member.

Fig. 4 is a central vertical section of Fig. 3.

Fig. 5 is a side elevation of the tool with 20 its members assembled in operative relation.

Fig. 6 is a central vertical section of Fig. 5.

Fig. 7 is a transverse section on line VII—VII of Fig. 6.

Fig. 8 is a transverse section on line VIII—25 VIII of Fig. 6.

Fig. 9 is a transverse section on line IX—IX of Fig. 6.

Fig. 10 is a side elevation of the jaw-member 30 of the tool showing a fragment of a sucker rod extending through the same, as when it is engaged by the tool to be withdrawn from the tubing.

In detail the construction set forth in said drawings is as follows:

The body of this tool consists of two members 35 namely, the upper or socket member 1 and the lower or tubular member 2, a chuck member, Fig. 2, is carried within said body. Said upper member consists of a cylindrical socket provided at the upper end with a screw-threaded stud, 3, by means of which the tool may be attached to the internally screw-threaded socket of a sucker rod or like element whereby it is lowered into and with-45 drawn from the tubing in the act of engaging with and withdrawing the sucker rod.

Below said stud 3 body 1 is provided with some suitable form of corrugation for engagement by a fishing tool should stud 3 be-50 come broken off or the tool become otherwise

severed from its actuating means and drop into the tubing; the lower end of said member 1, for a comparatively short portion of its length as indicated at 5 is reduced in diameter and said short portion is provided with an external screw thread for co-operation with the internal screw-thread 6 within the upper end of the lower body member 2. Said member 2 is a tubular element having a modified bore extending through the same; below said screw-threaded portion 6, the bore is formed with a downwardly-converging tapered portion 7, below which is a straight portion 8, which terminates in a shoulder 9, the remaining lower portion 10 of said bore 65 being somewhat larger than the diameter of the sucker rod to be operated upon.

The portions 7 and 8 of the bore of the member are adapted to receive the automatic chuck—Figs. 2 and 10—which comprises rod 70 gripping jaws 11 and a sleeve member 12; the periphery of said jaws 11 is formed with a downwardly converging taper for co-operation with the tapered wall 7 of the bore of the body member 2; the outside diameter of 75 sleeve 12 is somewhat smaller than and is free to have vertical movement in the portion 8 of said member 2.

The chuck body—Fig. 2—is provided with a plurality of longitudinally-extending slots 80 13, whereby the gripping head 11 of said chuck is adapted to have resilience for the purpose of expanding and contracting for gripping and releasing a sucker rod, as 14, which is being operated upon.

The internal, gripping faces 15 of the jaws of the chuck are knurled or roughened in some suitable manner to cause them to securely grip the rod, as 14. In the drawings the roughness is shown as being imparted to said faces 15 by tapping them with an internal left hand thread, said left hand thread being employed so that the chuck may be released from its grip upon the rod by unscrewing it through the medium of a sucker rod which 95 carries it, the joints of which are provided with right hand threads. The material in said chuck is steel, which is hardened after it is finished and, if a considerable degree of force is required to extract the sucker rod 100.

from the tubing, the threads of the jaw will become embedded somewhat into the rod, and in such a case the tool may be readily unscrewed from the rod. The internal diameter of the hole in said jaws 11 is slightly smaller than the diameter of the rod to be operated upon so that as the rod passes through the chuck it causes said jaws to expand somewhat.

10 It is pointed out that the elongated tubular sleeve 12 below, and which forms a portion of the jaw structure, is arranged to, conjointly with the portion 10 of the bore of member 2, constitute an elongated guide-socket which 15 serves as an approach to the jaws 11 whereby the adjacent end of a sucker rod is not only caused to be concentric with the gripping faces of said jaws but is also prevented from bending when the fishing tool is forced into 20 gripping relation therewith.

My improved sucker rod fishing tool is used in the following manner:

When a sucker rod which is in use in a well becomes broken, the fishing tool is screwed 25 into the socket of that portion of the rod that can be withdrawn from the well; it is then inserted and lowered into the tubing so that the end of the rod within the well enters the bore of the fishing tool and when the 30 end of the rod comes into contact with the lower edge of the jaws 15 of the chuck, the chuck is caused to rise until its upper face contacts with the lower face 16 of the upper member, whereupon, jaws 11 are caused 35 to expand and the rod 14 passes therethrough until its upper end contacts with the upper end of the bore 17. The tool is then raised and the first result of the upward movement of the tool is to cause the jaws 11 to seat in 40 the tapered portion 7 of the bore of the member 2; this seating action compresses and tends to contract the jaws and causes them to firmly grip the engaged sucker rod 14; a continued upward movement of the tool carries the rod with it to accessibility for removal 45 from the tubing in the usual way.

I claim the following:

In a fishing tool for sucker rods, a cylindrical body provided at its upper end with 50 means for attachment to an actuating means, also a bore extending into the lower end of said body forming a socket and chuck-chamber, said chamber being formed at its upper end with upwardly-diverging walls terminating at their upper limit in a shoulder, and a longitudinally-movable, cylindrical chuck within said chamber consisting of an elongated, tubular element adapted to be limited 55 in its upward movement by contact of its upper face with said shoulder, said chuck having at its upper end expandible and contractible jaws and a rod passage therebetween for contact and engagement with the periphery of a rod, said limit of the upward movement 60 of said chuck being for the purpose of

forcing said jaws over the rod to be operated upon, the outer peripheral faces of said chuck jaws having upwardly-diverging surfaces for contact with said diverging walls of said chamber when the tool is raised, as and for 70 the purpose set forth.

In testimony whereof I affix my signature.
ORVILLE J. THOMPSON.
